OPERATOR

William R. Ray, Beverly Hills, Calif.

Application July 27, 1940, Serial No. 348,064

8 Claims. (Cl. 60—52)

My present invention relates to improvements in an electrically controlled hydraulic operator for imparting to-and-fro movement to means to be operated, such as valve closure members, dampers, or the like.

An object of my invention is to provide an improved operator of the character described wherein the parts are compactly and effectively arranged, and which is completely sealed against leakage of the pressure-transmitting liquid.

Another object is the provision in an hydraulic operator, including an electrically operated pump, of switching means for breaking the pump-motor-energizing circuit upon predetermined movement of the operating member under the influence of the pump, which switching means is contained wholly within the pressure chamber of the operator. A further object is the provision of novel and effective means for actuating said switching means.

Another object is the provision, in an hydraulic operator of the character described, of electricaly operated valve means for relieving the generated liquid pressure and means, accessible from the exterior of the operator, for adjusting the rate of flow through said valve.

A still further object is the provision of a unitary pump and relief-valve structure which is particularly adapted for use in the operator of my present invention.

Other objects and advantages of my invention will be found in the description, the drawings, and the appended claims.

For complete understanding of the invention, reference may be had to the following detailed description and accompanying drawings, wherein:

Figure 1 is a diagrammatic view of an operator embodying my invention;

Figure 2 is a longitudinal sectional view of a 40 preferred form of the operator;

Figure 3 is a transverse section taken along the line 3—3 of Fig. 2;

Figure 4 is an enlarged fragmentary sectional view of the pump structure taken along the 45 line 4—4 of Fig. 2.

Figure 5 is an enlarged fragmentary transverse sectional view of the pump and relief-valve structure, taken along the line 5—5 of Fig. 2, and showing the relief-valve operating 50 means in elevation; and

Figure 6 is an enlarged longitudinal sectional view of the pressure-relief flow-adjusting means, taken along the line 6—6 of Fig. 3.

Referring first to the diagrammatic showing 55

of Fig. 1, the numeral 11 indicates a cylindrical casing provided intermediate its ends with a rigid immovable partition 12. Sealingly secured to the bottom end of the casing is a metallic bellows 13 which is provided at its upper end with a plate or wall 14. Secured to this plate is a stem 15 which is guided in an opening formed in a bottom plate 16 secured to the casing; a spring 17, compressed between this plate and 5 the movable plate or wall 14, urging the stem upward, its movement in this direction being limited by the engagement of an enlarged portion 18 of the stem with the plate 16.

The space within the casing above the partition 12 serves as a reservoir for a pressure-transmitting liquid such as oil; the casing wall being extended by a housing 19. Mounted in this reservoir is an electric-motor-operated pump, indicated by the legends, for forcing the liquid 10 through a pipe 20, sealingly extended through the partition, into the pressure chamber 21 defined by the lower portion of the casing, the bellows, wall 14 and partition 12. The pump is provided with an inlet 22, and a check valve 23 which 15 precludes return of the liquid through the pump. Branched from the pipe 20 is another pipe 24, with the open end of which a pivoted plate-like magnetic closure member 25 cooperates to form a relief valve, generally indicated by the numeral 26; 20 through a pipe 20, sealingly extended through the partition, into the pressure chamber 21 defined by the lower portion of the casing, the bellows, wall 14 and partition 12. The pump is provided with an inlet 22, and a check valve 23 which 25 precludes return of the liquid through the pump. Branched from the pipe 20 is another pipe 24, with the open end of which a pivoted plate-like magnetic closure member 25 cooperates to form a relief valve, generally indicated by the numeral 26; 30 an electromagnet 27 serving, when energized, to attract the closure member into valve-closing position. The electromagnet is connected by wires 28, through a switch 29, to a source of electrical energy 30; and the pump motor is connected by wires 31 to the same source, through switches 32 and 33. The latter switch comprises a contact blade 34, of resilient material, insulatingly mounted in the partition 12 and tensioned into engagement with a contact element 35, similarly mounted in the partition. The contact blade 34 is provided with an extension 36 with which the bent upper end portion of an arm 37, carried by the wall 14, is adapted to engage.

The operation of the device hereinabove described is as follows: If switches 29 and 32 are closed, relief valve 26 closes and the pump is operated by the motor, forcing liquid from the reservoir into the pressure chamber 21, which was also filled with liquid, with the result that the wall 14 is moved downward against the force of spring 17, collapsing the bellows. If the motor switch 32 (only) is opened, the wall is held in its lowered position by the liquid trapped in the pressure chamber, relief valve 26 being held

closed and return of liquid through the pump being prevented by check valve 23. If switch 29 is now also opened, the force of spring 17 moves the wall upward, forcing the liquid back into the reservoir through the open relief valve 26, electromagnet 27 being deenergized by opening of switch 29. The operating stem of the device can thus be moved to, and maintained in, any desired position within its range. If it is desired to operate the device only to its extreme moved positions, the switches 29 and 32 may be connected to operate conjointly. When the pump motor and the relief valve operator are then both energized, liquid is pumped into the pressure chamber and the wall is moved downward until the arm 37 engages the extension 36 of contact blade 34, opening switch 33 and thus stopping the pump motor. The relief valve still being held closed, the wall is maintained in its lowered position until the switches 29 and 32 are reopened to permit the liquid to return to the reservoir through the relief valve.

Referring now to Figs. 2-6 of the drawings, the numeral 40 indicates a cylindrical casing having intermediate its ends an inner annular flange portion 41 to which is secured a rigid metal plate 42, a washer 43 of electrical insulating material being interposed between the flange and the plate. Extending from the bottom of the casing, and integral therewith, is a pair of side walls 44 which terminate in an annular portion 45, to which is secured a disk 46. Threaded in a central opening in this disk, and locked in position by a nut 47, is a member 48 which is externally threaded at its lower end for attachment to a device to be operated, such as a fluid control valve. The member 48 has a bore for the reception of an operating stem 49, the stem being sealed from leakage of fluid from the operated device by packing 50 compressed around the stem by a nut 51 co-operating with a compression member 52.

The bottom of the casing 40 is provided with an inner annular flange 53, the underside of which is recessed to receive the folded-over marginal bottom end portion of a metallic bellows 54. The bellows is soldered in the recess and is additionally held in place by a dished plate 55 received in another recess in the flange and secured by a pair of taper pins 56 pressed in openings in the side walls 44. Secured by solder to the marginal top end portion of the bellows is another dished plate 57 having a downwardly formed annular center portion which is threaded to receive the threaded upper end portion of a stem 58 which extends downward and is guided in a bushing 59 secured in a central opening in plate 55. The end portion of stem 58 below plate 55 is enlarged to provide a shoulder 60 which, by engagement with the bushing, limits upward movement of the stem. The upper end of stem 49 is provided with a head nut 61, tightly threaded thereon, which is freely received in a recess formed in the bottom of stem 58. The two stems are loosely connected together by a shoulder nut 62 threaded on the enlarged lower end portion of stem 58. By this loose connection, possible binding, due to slight misalignment of the stems, is prevented. A spring 63, compressed between the plates 55 and 57, urges the stems upward. An opening 64 in plate 55 permits passage of air into and out of the space within the bellows when the same is expanded or contracted. The lower portion of the casing 40 defines, with the bellows, plate (or "movable

wall") 57 and partition 42, a pressure chamber 65.

The portion of casing 40 which extends above the partition 42 forms therewith a reservoir 66 for the pressure-transmitting liquid, which is preferably oil. Mounted in this reservoir on the partition 42, by spacers 67, is an electric motor 68, preferably of the brushless alternating-current type. This motor comprises a laminated core 69 and an energizing coil 70, and has a drive shaft 71 to which is secured a head 72. A plate 73 is mounted on the core 69 by screws 74 threaded in spacers 75 riveted to the plate.

Secured to this plate by screws 76 is a rectangular block of metal 77. As is shown in Figs. 4 and 5, this block is bored to provide a cylinder 78 for a piston 79. A connecting rod 80 is pivoted at one of its ends on the piston and at its other end on a pin 81, eccentrically mounted in the motor drive head 72. The piston has a longitudinal bore 82 which is enlarged at its inner end for the reception of a ball 83 which is pressed by a spring 84 against a seat formed by the junction of the bore 82 and its enlargement, a hollow plug 85 threaded in the inner end of the enlargement holding the spring compressed. Branched from the inner end of the cylinder is a horizontal passage 86 which communicates with another horizontal passage 87, parallel with the cylinder. The outer end of this passage is enlarged and is closed by a screw plug 88. At the inner end of this enlarged passage is a ball 89 which is held against the seat there-formed by a spring 90 compressed between the ball and the plug 88. Threaded in a side wall of the block 77, and communicating with the enlargement of passage 87, is a hollow fitting 91. The arrangement just described constitutes a pump, controlled in its action by the check valves formed by the balls 83 and 89. When the piston is reciprocated by the motor, in the outward stroke liquid is drawn into the piston (from the reservoir) through the bore 82 past the ball 83, passage of liquid in the opposite direction being prevented by the ball 89. In the inward stroke, the liquid is forced past the ball 89 and through the fitting 91, ball 83 preventing passage of liquid in the opposite direction. Soldered to the fitting 91 is a pipe 121, the lower end of which extends through an opening in the partition 42 and is secured there-in by solder.

Communicating with the horizontal passage 87, at the discharge side of the ball check 89, is a vertical passage 92. Another vertical passage 93 communicates with a horizontal passage 94, the outer end of which is enlarged to receive, and provide a seat for, a relief-valve ball 95. Interconnecting the passages 92 and 93, by pipes 96 and 97, is a metering valve structure 98 which comprises a body 99 threaded in an opening in the upper side wall of the casing 40 and secured thereto by solder. The body is provided at its inner end with vertical inlet and outlet passages 100 and 101, respectively, separated by a partition 102 having a port opening 103 therethrough. Threaded in a horizontal bore 104 axially aligned with the port opening, and adjustable from the exterior of the casing, is a closure member 105 having a conical end portion cooperable with the port opening. The outer end of the bore 104 is enlarged to receive packing 106 which is compressed around the stem of the closure member by a nut 107, a cap

108 being provided as additional protection against leakage from the valve. So as to prevent fluid passage through the metering valve being completely obstructed by the closure member, a right-angled restricted passage 109, bypassing the inlet and outlet, is drilled in the end portion of the closure member. The pipes 96 and 97, which connect, respectively, the inlet and the outlet passages of the metering valve with the passages 92 and 93 in the block 77, are secured at their either ends in these passages by solder.

Also secured to the plate 73, by screws 110, is an electromagnetic device 111 which comprises a core having a shaded pole 112 and an energizing coil 113. Pivotally mounted on a bracket 114 for attraction by the pole is an armature 115. Loosely extending through an opening in a rear portion of the armature is a vertical rod 116 which is pivotally connected at its bottom end to a bell-crank 117 mounted on a support 118 riveted to the plate 73. A spring 119, compressed between the upper surface of the rear portion of the armature and a head 120 provided on the top end of rod 116, urges the vertical portion of the bell-crank into light engagement with the relief-valve bail 95. This spring also serves to bias the armature away from the pole. In the upper end of the pressure chamber 63 is a switch 122, comprising a blade 123, of resilient material, insulatingly mounted on the underside of the partition 42 and carrying a contact element 124 cooperable with, and tensioned by the blade into engagement with, another contact element 125, directly mounted on the partition. Means for actuating this switch is provided by a screw 126 secured at its upper end to the free end of blade 123 and extending downward within a bore 127 formed in the upper end portion of the stem 58; a bushing 128, threaded in the outer end of the bore, freely surrounding the shank of the screw. When the stem 58 is moved downward through a distance determined by the length of the screw, the underside of the bushing engages the screw head 129, moving the blade downward to open the switch. By this arrangement of the switch there are no movable mechanical connections between the pressure chamber and the reservoir which might introduce leakage, as would be the case if the switch were mounted in the reservoir.

The electric motor and the coil of the electromagnetic relief-valve operator are connected to terminals 130, 131 and 132, insulatingly and sealingly mounted in a thickened upper portion of the casing, each of the terminals having a thin integrally-formed enlargement 133 which is clamped between insulating washers in the casing opening by a nut 134. One lead 135 of the motor and one lead 136 of the electromagnet coil are brought to a common terminal 131, the other lead 137 of the coil being connected to terminal 130. The other lead 138 of the motor is connected to the switch contact 125, a lead 139 connecting the switch blade to the terminal 132. A terminal box 140, having a cover plate 141, is secured to the casing.

A reservoir housing 142, provided with a filler-plug 143, is secured to the top of the casing by solder.

The general operation of the device shown in Figs. 2-6 is the same as that of the device diagrammatically shown in Fig. 1, which operation was hereinbefore described and therefore will not be repeated. In regard to the relief valve com-

10 prising the ball 95, when the electromagnetic device 111 is energized, the armature is attracted, compressing the spring 119, force sufficient to hold the ball tightly against its seat thus being exerted by the bell-crank. When the electromagnet is deenergized, the compressed liquid is able to move the ball away from its seat against the light force now exerted by the spring through the bell-crank. The purpose of the metering valve 98, interposed in the relief valve fluid circuit, is to adjust the rate of return movement of the operator as desired; accidental complete stoppage of the operator being prevented by the restricted by-pass 109 across the metering valve.

15 While I have herein shown and described a specific embodiment of my invention, I wish it to be understood that modifications may be made without departing from the spirit of the invention, and that I intend therefore to be limited 20 only by the scope of the appended claims.

I claim as my invention:

1. In an operator of the character described, in combination: an elongated casing; a rigid partition joining the side walls of said casing intermediate the ends thereof; a movable wall joined to the lower end of said casing; the lower portion of said casing defining, with said partition and said wall, a pressure chamber; the upper portion of said casing defining, with said partition, a reservoir containing a liquid; an electrically operated pump in said reservoir, and supported by said partition, for forcing said liquid into said chamber to move said wall in one direction; and means constantly urging said wall in an opposite direction.

2. In an operator of the character described, in combination: an elongated casing; a rigid partition joining the side walls of said casing intermediate the ends thereof; a movable wall joined to the lower end of said casing; the lower portion of said casing defining, with said partition and said wall, a pressure chamber; the upper portion of said casing defining, with said partition, a reservoir containing a liquid; an electrically operated pump in said reservoir, and supported by said partition, for forcing said liquid into said chamber to move said wall in one direction; means constantly urging said wall in an opposite direction; and switching means 40 mounted on the underside of said partition, and actuated by predetermined movement of said wall in said one direction, for controlling the energization of said electrically operated pump.

3. In an operator of the character described, in combination: an elongated cylindrical casing; a rigid partition joining the side wall of said casing intermediate the ends thereof; an expansible-contractible bellows in the lower portion of said casing and joined to the side wall thereof at its lower end; a movable wall joined to the upper end of said bellows; said lower portion of said casing defining, with said bellows, said wall and said partition, a pressure chamber; an operating stem operatively connected to said wall and extending downward within said bellows; the upper portion of said casing defining, with said partition, a reservoir containing a liquid; an electrically operated pump wholly in said reservoir, and supported by said partition, for forcing said liquid into said chamber to move said wall in a downward direction; and means constantly urging said wall in an upward direction.

4. In an operator of the character described, in combination: a cylindrical casing; an ex-

5
pansible-contractible bellows in said casing and joined to the side wall thereof at its lower end; a movable wall joined to the upper end of said bellows; said casing defining, with said bellows and said wall, a pressure chamber; an operating stem operatively connected to said wall and extending downward within said bellows; a reservoir containing a liquid and mounted on said casing; an electrically operated pump, mounted in said reservoir, for forcing said liquid into said pressure chamber to move said wall in a downward direction; means constantly urging said wall in an upward direction; a normally-open electrically operated relief valve interconnecting said pressure chamber and said reservoir; energizing circuits for said pump and for said valve; normally-closed switching means, connected in said pump-energizing circuit, mounted wholly in said pressure chamber; and means received in a longitudinal opening formed in the upper end portion of said stem for actuating said switching means to break said pump-energizing circuit upon predetermined movement of said wall in said downward direction.

5. In an operator of the character described, in combination: an elongated casing; a rigid partition joining the side walls of said casing intermediate the ends thereof; a movable wall joined to the lower end of said casing; the lower portion of said casing defining, with said partition and said wall, a pressure chamber; the upper portion of said casing defining, with said partition, a reservoir containing a liquid; an electric motor in said reservoir and supported by said partition; a pump mounted on said motor and driven thereby; means fluidly connecting said pressure chamber with the outlet of said pump; said pump being adapted to force said liquid through said connecting means into said chamber to move said wall in one direction; means constantly urging said wall in an opposite direction; an electrically operated relief valve in said reservoir; means fluidly connecting said pressure chamber with the inlet of said valve; energizing circuits for said pump motor and said valve; and normally-closed switching means mounted on the underside of said partition and actuated by the movement of said wall for breaking said pump-motor-energizing circuit upon predetermined movement of said wall in said one direction.

6. In an operator of the character described, in combination: an elongated cylindrical casing; a rigid partition joining the side wall of said casing intermediate the ends thereof; an expansible-contractible bellows in the lower portion of said casing and joined to the side wall thereof at its lower end; a movable wall joined to the upper end of said bellows; said lower portion of said casing defining, with said bellows, said wall and said partition, a pressure chamber; an operating stem operatively connected to said wall and extending downward within said bellows; the upper portion of said casing defining, with said partition, a reservoir containing a liquid; an electric motor in said reservoir and supported by said partition; a pump mounted on said motor and driven thereby; means fluidly connecting said pressure chamber with the outlet of said pump; said pump being adapted to force said liquid through said connecting means into said chamber to move said wall in one direction; means constantly urging said wall in an opposite direction; an electrically operated relief valve in said reservoir and having an outlet thereinto; means fluidly connecting said pressure chamber with the inlet of said valve; additional valve means in said last-named connecting means, and mounted in a wall of said reservoir, for adjusting the rate of flow through said relief valve; said adjusting valve being operable exteriorly of said casing; and means defining a restricted passage by-passing said adjusting valve.

let of said pump; said pump being adapted to force said liquid through said connecting means into said chamber to move said wall in a downward direction; means constantly urging said wall in an upward direction; an electrically operated relief valve in said reservoir; means fluidly connecting said pressure chamber with the inlet of said valve; energizing circuits for said pump motor and said valve; and normally closed switching means mounted on the underside of said partition and actuated by the movement of said wall for breaking said pump-motor-energizing circuit upon predetermined downward movement of said wall.

15 7. In an operator of the character described, in combination: an elongated casing; a rigid partition joining the side walls of said casing intermediate the ends thereof; a movable wall joined to the lower end of said casing; the lower portion of said casing defining, with said partition and said wall, a pressure chamber; the upper portion of said casing defining, with said partition, a reservoir containing a liquid; an electric motor in said reservoir and supported by said partition; a pump mounted on said motor and driven thereby; means fluidly connecting said pressure chamber with the outlet of said pump; said pump being adapted to force said liquid through said connecting means into said chamber to move said wall in one direction; means constantly urging said wall in an opposite direction; an electrically operated relief valve in said reservoir and having an outlet thereinto; means fluidly connecting said pressure chamber with the inlet of said valve; and additional valve means in said last-named connecting means, and mounted in a wall of said reservoir, for adjusting the rate of flow through said relief valve; said adjusting valve being operable exteriorly of said casing.

30 8. In an operator of the character described, in combination: an elongated casing; a rigid partition joining the side walls of said casing intermediate the ends thereof; a movable wall joined to the lower end of said casing; the lower portion of said casing defining, with said partition and said wall, a pressure chamber; the upper portion of said casing defining, with said partition, a reservoir containing a liquid; an electric motor in said reservoir and supported by said partition; a pump mounted on said motor and driven thereby; means fluidly connecting said pressure chamber with the outlet of said pump; said pump being adapted to force said liquid through said connecting means into said chamber to move said wall in one direction; means constantly urging said wall in an opposite direction; an electrically operated relief valve in said reservoir and having an outlet thereinto; means fluidly connecting said pressure chamber with the inlet of said valve; additional valve means in said last-named connecting means, and mounted in a wall of said reservoir, for adjusting the rate of flow through said relief valve; said adjusting valve being operable exteriorly of said casing; and means defining a restricted passage by-passing said adjusting valve.

WILLIAM R. RAY.
